UNITED STATES PATENT OFFICE

2,574,799

SIDE DITCH SCRAPER FOR DITCHING MACHINES

Emmett R. Seward, Houston, Tex.

Application February 18, 1949, Serial No. 77,244

1 Claim. (Cl. 37—80)

1

An object of this invention is to provide a pair of scrapers for mounting on any make or type of ditcher, such as the endless chain or wheel type, whereby the dirt, on either side of the ditch being dug, may be scraped into the ditch.

Another object of this invention is to provide a simplified adjusting and supporting means for scrapers.

A further object of this invention is to provide a scraper construction which may be adjusted relative to the ditching machine so as to be capable of use with any ditch, regardless of its depth or width.

A further object of this invention is to construct a side ditch scraper with a supporting plate quadrant having a long straight side adjacent the ditch whereby the same may be used on small and narrow constricted ditches.

A further object of this invention is to construct a side ditch scraper with supporting bars that can be fastened to any make or type of ditching machine, without alteration of the machine.

A further object of this invention is to construct a side ditch scraper having interchangeable bearing plates and angle bars to be used on either the right or left-hand side of the machine.

Still another object of the invention is the provision of a side ditch scraper including supporting plates for the blades thereof comprising an improvement over the construction disclosed in my prior Patent No. 1,831,324, dated November 10, 1931, entitled Side Ditch Scraper for Ditchers.

With the above and other objects in view, my invention consists in the arrangement, combination and details of construction disclosed in the drawings and specification, and then more particularly pointed out in the appended claim.

In the drawings,

Figure 1 is a detail side elevation of a side ditch scraper constructed according to an embodiment of this invention, showing the device mounted on a ditch digging device such as the device shown in my prior Patent No. 1,831,324 supra.

Figure 2 is a detail rear elevation of the device.

Figure 3 is a fragmentary plan view of one of the scrapers and the supporting means therefor.

Figure 4 is a fragmentary side elevation showing the adjustable mounting for the scraper blade.

Figure 5 is a sectional view taken on the line 5—5 of Figure 3.

Figure 6 is a fragmentary sectional view taken on the line 6—6 of Figure 3.

Figure 7 is a fragmentary sectional view taken on the line 7—7 of Figure 5.

2

Figure 8 is a fragmentary sectional view taken on the line 8—8 of Figure 3.

Referring to the drawings, the numeral 10 designates generally a ditch digger which includes an endless chain 11 having digging buckets 12 secured thereto, and operated by means of a driving chain 13 extending forwardly and connected to a suitable power means. Side plates 14 extend from the frame 10 and the digger 10 also includes an upright frame member 15 having fixed to the upper end thereof a rearwardly extending brace bar 16 and an angularly disposed bracing bar 17 which is in turn braced by means of a second bracing bar 18.

The digger 10 has secured to the rear end thereof a pair of scraping blades 19 and 20. These blades 19 and 20 are disposed in forwardly divergent relation and are adjustably secured to the frame of the digger as will be hereinafter described. Each blade and the supporting means therefor is identical and the detailed description of one of these blades with its supporting means will apply equally as well to the other blade and supporting means therefor.

The blade 20 has disposed thereabove a horizontally disposed bearing plate 21 which is secured to the blade 20 by means of inner and outer bars 22 and 23 and an intermediate bar 24. The bars 22 and 23 are provided with right angularly disposed upper ends 25 and 26 secured to the plate 21 by fastening means 27 and 28 respectively.

The upper end of the bar 24 is formed with a right angular member 29 which is secured to the plate 21 by means of a bolt 30, and the bolt 30 also constitutes a pivot bolt as will be herein-after described. The bars 22, 23 and 24 are formed with longitudinally curved lower portions 31, 32 and 33, engaging the rear convex side of the blade 20 and secured thereto by fastening means 34. Preferably the blade 20 is formed with spaced holes 35 so that the supporting bars 31, 32 and 33 may be adjusted along the length of the blade 20 to thereby position the inner end of the blade 20 in the desired position with respect to the edge of the ditch which is being formed by the digger.

The blade 20 is supported rearwardly of the digger 10 by means of a pair of rearwardly convergent supporting bars 36 which are mounted on a laterally extending shaft 37 formed with a right angularly disposed inner end 38 secured by fastening means 39 to an adjacent portion of the digger 10. The bars 36 each have secured to the inner end thereof a collar 40 through which a set screw 41 engages so that the bars 36 may be

adjusted along the length of the shaft 37. The outer end of the shaft 37 is supported by means of a downwardly and outwardly inclined bracing and supporting bar 42 which is secured by fastening means 43 to an adjacent portion of the digger which in the present instance includes a longitudinally curved gear rack 44 fixed to and extending downwardly from the boom bracing member 17.

An intermediate supporting bar 45 is disposed between the supporting bars 36 with the rear ends of the supporting bars 36 being disposed on opposite sides of the rear end of supporting bar 45. The forward end of bar 45 loosely engages the shaft 37 and the bars 36 and 45 are held in spaced apart relation by means of spacer sleeves 46 through which an elongated bolt 47 extends. A horizontally disposed angle bar 48 is secured to the rear ends of the bars 36 and 45 and the angle bar 48 includes a vertical side 49 which is formed, as shown in Figure 4, with a plurality of horizontal elongated slots 50 through which bolts 51 extend. The holes 50 provide a means whereby the scraper blades may be adjusted toward or away from the rear end of the ditcher to conform with the angle or the bucket line in deep or shallow ditches. The vertical side 49 of the angle bar 48 is interposed between the rear end of one of the supporting bars 36 and the adjacent side of the supporting bar 45. The pivot bolt 30 for the plate 21 extends through the rear portion of the horizontal lower side 52 of the angle member 48 and the bearing plate 21 is formed with an elongated arcuate slot 53 which is coaxial with the pivot 30. A bolt 54 extends through the horizontal lower side 52 of the angle bar 48 and through the slot 53 so that the bearing plate 21 may be angularly adjusted about the axis of bolt 30 to thereby vary the angular relation of one blade relative to the other.

The blades 19 and 20 may be vertically adjusted to either operative or inoperative position by means of a winding drum generally designated as 55. The winding drum 55 includes a shaft 56 which is journaled in bearings 57 which are carried by an inverted U-shaped member 58 which is formed with a downturned end 59 secured by fastening means 60 to the vertical side 49 of the angle bar 48. The drum 55 includes a hub 61 which is fixed to the shaft 56 and one end of the drum 55 is formed with ratchet teeth 62 with which a pawl 63 is adapted to engage for holding the drum 55 against rotation in an unwinding direction.

The pawl 63 is carried by a portion of the bearing structure 57 as shown in Figure 6. The drum 55 is adapted to have a cable 64 wound thereabout, the cable 64 being extended upwardly from the drum 55 and passed over a grooved pulley 65 which is rotatably carried by the rear end of the brace 16. The cable 64 is then extended downwardly and secured to an eye or other fastening means 66 which is carried by the winding drum base 58.

In the use and operation of this device, the scraping blades 19 and 20 are secured to the rear portion of the digger 10 as hereinbefore described. When the digger is in operation and the buckets 12 are moving and discharging the dirt into the lateral conveyor (not shown), the digger

will move forwardly slowly and at this time the scraping blades 19 and 20 will be disposed in their lower operative position substantially contacting with the surface of the ground. The blades 19 and 20 are laterally adjusted by means of the set screws 41 so that the inner ends of the blades 19 and 20 will be closely adjacent the side walls of the ditch which is being formed by the digger. In the event the blades 19 and 20 are to be adjusted toward or away from each other a distance greater than permitted by the length of the supporting shafts 37, the blades may be adjusted by removing the fastening means 34 and positioning the curved bars 31, 32 and 33 in adjusted position along the lengths of the blades. Normally the shafts 37 provide for scraping of the loose dirt into the ditch and in a position for removal of this loose dirt by the digging buckets 12 as the digger moves along the ground. In the event it is desired to vary the angular relation of one blade relative to the other, this may be done by loosening bolt 54 and swinging one of the bearing plates 21 to provide a desired angular position of the associated digging blade. The use of plate 21 will permit the adjustment of the scraper blades for use with small and narrow ditchers, and the substantial distance between pivot bolt 30 and bolt 54 will hold the scraper rigid in a non-tilting position.

I do not mean to confine myself to the exact details of construction herein disclosed, but claim all variations falling within the purview of the appended claim.

What I claim is:

A side ditch digger comprising a pair of scraper blades and supporting means for securing said blades to the digger, said supporting means including a pair of elongated divergent bars and a central bar for each blade, an angle iron secured to each set of bars, means for longitudinally adjusting the position of each of said angle irons relative to said bars, a plate having a relatively long arcuate edge and an obtusely angled edge positioned over each of said scraper blades, angle irons secured to each end and to the center of each of said scraper blades, a pivot bolt extending through said first-mentioned angle iron, said plate adjacent the angle of the obtusely angled edge thereof and said angle iron secured to the center of said scraper blade, each of said plates having an arcuate slot therein adjacent the arcuate edge coaxial with said pivot bolt, a second bolt extending through its associated first-mentioned angle iron spaced from its associated first-mentioned bolt and extending through the adjacent arcuate slot whereby the angular relation of said blades relative to their associated first-mentioned angle irons may be independently varied.

EMMETT R. SEWARD.
